UNITED STATES PATENT OFFICE.

CHARLES A. WHIPPLE, OF ELK RIVER, AND CHARLES A. JOHNSON, OF ALEXANDRIA,
MINNESOTA.

EVENER-BAR.

No. 926,917.

Specification of Letters Patent.

Patented July 6, 1909.

Application filed January 27, 1908. Serial No. 412,916.

To all whom it may concern:

Be it known that we, CHARLES A. WHIPPLE and CHARLES A. JOHNSON, citizens of the United States, residing at Elk River, in 5 the county of Sherburne and State of Minnesota, and Alexandria, in the county of Douglas and State of Minnesota, respectively, have invented certain new and useful Improvements in Evener-Bars, of which 10 the following is a specification.

Our invention relates to improvements in evener bars, its object being particularly to provide an improved construction of evener bar which will relieve the strain upon the 15 supporting pin and which will bring the pull of the tugs in line with the center of draft thereby preventing the tendency to turn the evener bar upon the pole as in the ordinary construction.

20 In the drawings Figure 1 is a perspective view of our invention shown applied to a wagon pole with the tongue broken away, and Fig. 2 is a vertical cross section of the evener bar adjacent to the pole.

25 Our improved evener is made of two parts A and B adapted to be arranged above and below the pole. The upper part A consists of a central block 2 having a flat bottom to rest upon the pole and supporting in its upper front end a rod or pipe 4 and at its rear end a rod 5 said rods being connected together at their outer ends by pin receiving plates 6. The lower member of the evener is similarly composed of a central block 7 30 having an upper flat surface to bear against the underside of the pole. The block 7 supports a rod or bar 8 and a rod 9 corresponding to the rods 4 and 5 connected at their ends by pin receiving plates 10 corresponding to the plates 6. The evener members are secured upon the pole by means of the pin 11 extending through the blocks 2 and 7 a hammer strap 12 of ordinary construction receiving the upper end of the pin.

45 As will be noted by referring to Fig. 2 of the drawings the front side of the upper evener member stands some distance to the

rear of the front side of the lower evener member and the upper rod 4 is supported some distance above the pole whereas the 50 bar or rod 8 of the lower member is supported close to the underside of the pole. Also it will be noted that the rod 5 of the upper evener member is supported much closer to the pole than is the rod 9 of the 55 lower evener member. The result of these features of construction and arrangement is that the clevis pins that pass through the socket plates 6 and 10 will stand at right angles to the arrow line of Fig. 2, the arrow 60 line of Fig. 2 being therefore the line of draft. The object of this is to have the line of draft in line with the direction assumed by the tugs in running from the horse to the whiffle-trees. The construction of the two evener 65 bars above described also gives the greatest strength or resistance directly in the line of draft and obviates the rolling tendency of the evener bar which exists in the ordinary construction. 70

We claim:

1. In combination with a wagon pole, an evener bar comprising a pair of independent members arranged one above and one below the pole, said members having their outer 75 ends superimposed and with the central front face of the upper member standing at the rear of the central face of the lower member so as to provide an upwardly directed draft, and whiffle tree supporting means carried by 80 the outer ends of said members.

2. An evener bar of the class described, comprising a pair of independent members carrying whiffle tree supporting means at their ends, each member being centrally supported upon a bearing block with the outer ends of the members superimposed, and with the central front face of the upper member standing to the rear of the central face of the lower member so as to provide an upwardly 85 directed draft, for the purpose set forth. 90

3. In combination with a wagon pole, an evener bar comprising a pair of skeleton members one arranged above and one below

the pole, whiffle tree supporting means carried by the outer ends of said members and each of said members consisting of a central bearing plate supporting a front horizontal 5 rod and a rearwardly inclined bent brace rod, said brace rods being supported below the horizontal planes of said front rods, and the front rod of said upper member standing at the rear of the front rod of said lower 10 member, for the purpose set forth.

In testimony whereof we affix our signatures in presence of two witnesses.

CHARLES A. WHIPPLE.

CHARLES A. JOHNSON.

Witnesses as to Charles A. Whipple:

CHAS. M. BABCOCK,

CHAS. W. CATER.
